UNITED STATES PATENT OFFICE.

STANLEY M. LAWSON, OF CINCINNATI, OHIO.

DESIGN FOR A CLOCK-FRAME.

No. 38,011.

Specification for Design.

Patented May 15, 1906.

Application filed March 28, 1906. Serial No. 308,624. Term of patent 3½ years.

To all whom it may concern:

Be it known that I, STANLEY M. LAWSON, a citizen of the United States, residing at Cincinnati, Hamilton county, State of Ohio, have invented a certain new, original, and ornamental Design for a Clock-Frame, reference being had to the accompanying drawings, which show my design, Figure 1 being a front view, and Fig. 2 a side view, thereof.

I claim—
The ornamental design for a clock-frame as shown.

STANLEY M. LAWSON.
